MOVING STAIRWAY HAND RAIL CONSTRUCTION

Russell G. Tilton, Mountain Lakes, N.J., assignor to Multiscope, Inc., Brooklyn, N.Y., a corporation of Kansas

Application August 19, 1954, Serial No. 450,968

4 Claims. (Cl. 198—16)

The present invention relates to a hand rail construction in conjunction with moving stairways, providing a means for riders or passengers on the stairway to steady themselves while riding the stairs.

In my copending application, Serial No. 331,570, filed January 16, 1953, now patent No. 2,766,868, there is disclosed a hand rail for a moving stairway, which consists essentially of a plurality of companion members with means being provided for connection thereof with a continuous hand rail chain for transmitting power to the companion members of the hand rail.

The principal object of the present invention, generally stated, is to provide a smooth, continuous hand rail made in a single piece, in which the structure responds to movement about an orbit in like manner to that in the above-mentioned application.

Another object of the invention is the provision of a continuous hand rail having means incorporated therein, with said means preventing stretching and elongation of the hand rail.

Another object is the provision of a hand rail made of a material lending itself to the extrusion process rather than the molding process.

A further object is the provision of a hand rail construction having a positive driving means incorporated therein.

Further objects and particular advantages of the invention will suggest themselves in the course of the following description, and that which is new will be pointed out in the appended claims.

The preferred embodiment of the invention is illustrated in the accompanying drawings, in which:

Figure 1 is a side elevation of a portion of a hand rail assembly embodying the features of the invention.

Figure 2 is a cross section through the hand rail assembly, taken on line 2—2 of Figure 1.

Figure 3 is an isometric view of one of the chain attachment plates.

Figure 4 is a detail cross section through the hand rail member.

Figure 5 is a detail longitudinal section through the hand rail member, taken on line 5—5 of Figure 4.

Figure 6 is a detail plan view of the hand rail driving chain showing the chain attachment plates in connection therewith.

Figure 7 is a detail side elevation of the assembled drive chain, taken from line 7—7 of Figure 6.

Like characters of reference denote like parts throughout the several views of the drawing.

In order that the construction of the hand rail and the elements thereof may be more fully understood and appreciated, I will now take up a detailed description thereof.

Referring now to the drawing in detail, the hand rail member 11 is composed of extruded material such as rubber, plastic, or other suitable material of such length to complete an orbit in connection with a moving stairway. Apertures 12 are formed therein throughout the

2

length of the hand rail. The apertures are provided in the hand rail for the purpose of reducing the volume of material and may be of any suitable shape. A chain-receiving channel 13 is formed in the hand rail with the same being open toward the inside of the orbit of the hand rail. Comparatively smaller channels 14 and 15 are formed outwardly from the chain-receiving channel 13 with channels 14 and 15 being formed continuously throughout the length of the hand rail and with the channels 14 and 15 providing for the reception of an engaging portion of each of the chain attachment plates.

The driving portion of the hand rail construction is composed of a chain having rollers 16 with pins 17 and connected by means of chain links 18 and chain attachment plates 19, as more clearly shown in Figures 6 and 7. Each of the chain attachment plates 19 has an upper lug 20 and a lower lug 21 formed integrally therewith, as shown in Figure 3, with the upper lugs 20 thereof being adapted to frictionally engage the respective channels 14 and 15 of the hand rail member.

The upper run of the hand rail assembly is provided with a track 22 on which rollers 16 ride and which is of such width to fit neatly between the chain attachment plates 19 with the track being supported on an inwardly-extending flange 23 of side plate 24, and with screws 25 providing means securing the track on the flange. An auxiliary track 26 is secured on the inner side of plate 24 by means of screws 27, as indicated in Figure 2, with there being sufficient space provided between the upper surface of flange 23 and the under side of track 26 for the movement of the lower lugs 21 of the chain attachment plates 19.

Side plate 24 is removably secured to an upwardly-turned flange 28 of deck-receiving member 29 by means of screws 30. Deck-receiving member 29 has a continuous rib 31 formed thereon rigidly supporting the inner portion of flange 23 of side plate 24. The deck-receiving member also has an upwardly-extending side member 32 formed thereon, with the upper portion thereof being adapted to coincide with the adjacent surface of the hand rail. A second auxiliary track 33 is secured to side member 32 by means of screws 34, as more clearly shown in Figure 2. Numeral 35 indicates a deck base plate to which deck-receiving member 29 is secured by means of screws 36. 37 denotes deck trim which has one edge thereof secured to deck-receiving member 29 in any suitable manner.

In the assembly of the hand rail, with the driving chain being assembled as shown in Figures 6 and 7, the lower portions of the hand rail 11 are spread sufficiently to permit the entrance of lugs 20 into their respective channels 14 and 15. Track 22 is brought into contacting relation with rollers 16, after which side plate 24, with its auxiliary track 26, is brought into position and track 22 is secured thereto by means of screws 25, thus forming a sub-assembly composed of members 11, 16, 17, 18, 19, 20, 21, 22, 24 and 26. With members 29, 33, 35 and 37 having been previously assembled and in place, the sub-assembly is brought into position and secured to the upwardly-turned flange 28 of deck-receiving member 29 by means of screws 30.

It is to be understood that the ends of the hand rail 11 are brought together in abutted relation and vulcanized or otherwise secured together.

Should it be necessary to remove the hand rail assembly, screws 30 may be removed, after which the sub-assembly may be removed from its position with relation to the deck-receiving member 29.

Hand rail member 11, being formed by the extrusion process, is much more economical than hand rails made by the molded process.

3
Operation

In the operation of the hand rail, sprockets (not shown) are provided at the upper and lower levels of the stairway, with either the upper sprocket or the lower sprocket being driven by a power means (not shown). The hand rail chain engages the sprockets and is driven by one of the sprockets. Hand rail member 11 is carried by the chain through the frictional engagement of lugs 20 in the respective channels 14 and 15 without there being any driving stress imposed on the hand rail member.

The chain, together with the hand rail member, is carried on track 22 while auxiliary tracks 26 and 33 prevent upward movement of the chain or hand rail by reason of lugs 21 being located below the auxiliary tracks. It will be noted that the upper portions of side plate and upwardly-extending side member 32 are formed to closely coincide with the profile of the adjacent portions of the hand rail and thus preventing dislodgement of the hand rail by riders of the moving stair.

I desire that it be understood that I am not to be limited to the specific design of the parts or to the arrangement of the same as herein shown and described, but that minor changes and modifications may be made therein, insofar as the changes or modifications may fall within the scope of the appended claims.

Having now shown and described the invention, what I claim and desire to secure by Letters Patent of the United States, is:

1. In a moving stairway hand rail, an extruded hand rail member provided with a driving chain recess, a driving chain having chain attachment plates forming a part thereof with each of the chain attachment plates having an outwardly-directed lug formed thereon, a track supporting the driving chain with said track being secured to a side plate member, a second outwardly-directed lug formed on each of the chain attachment plates with the second lug having a curved upper surface, and with an auxiliary track member being located above the second outwardly-directed lugs and providing means preventing movement of the driving chain away from its track by contact therewith of the curved upper surface of the second lugs.

4

2. In a moving stairway hand rail construction, a sub-assembly composed of a driving chain having an extruded hand rail member frictionally secured thereto, a track member secured to a side plate member, a pair of auxiliary tracks preventing dislodgement of the chain from its track, and means removably securing the sub-assembly to a deck-receiving member.

3. A moving stairway hand rail construction as set forth in claim 2, and with the hand rail member being of extruded construction and having a pair of opposed continuous inwardly-opening chain receiving channels formed longitudinally thereof.

4. In a moving stairway hand rail construction, a deck-receiving member, a side plate removably secured to the deck-receiving member and having an inwardly-extending flange formed integrally therewith, a track member removably secured on the upper surface of the inwardly-extending flange, an auxiliary track secured to each of the deck-receiving member and the side plate, an extruded hand rail member adapted to ride over and cover the upper portions of the deck-receiving member and the side plate, with the extruded hand rail member having a chain-receiving channel formed longitudinally thereof, a pair of chain lug-receiving channels formed longitudinally of the extruded hand rail member with the chain lug-receiving channels being in opposed relation and communicating with the chain-receiving channel, a drive chain located within the chain-receiving channel of the extruded hand rail member and running on the track member, with channel-engaging lugs being formed on the drive chain and frictionally engaging the extruded hand rail member in the opposed channels thereof, and with secondary lugs formed on the drive chain and being adapted to engage the auxiliary tracks.
